UNITED STATES PATENT OFFICE.

RICHARD FITZ POWER, OF HAMPSTEAD, LONDON, ENGLAND, ASSIGNOR TO MORLAND & IMPEY LIMITED, OF BIRMINGHAM, ENGLAND.

LOOSE-LEAF-BINDING MECHANISM.

Original application filed January 29, 1926, Serial No. 84,598, and in Great Britain May 25, 1925. Divided and this application filed May 10, 1927. Serial No. 190,324.

This invention relates to improved loose leaves and to securing or binding mechanism therefor, more particularly of file form, and my improved construction provides, firstly, 5 leaves of such form that they can be cut from a long sheet without waste, secondly, for the ready removal of a leaf or leaves from the securing or binding mechanism, and, thirdly, a binder, the anchoring members whereof 10 move automatically to locking position when free.

This application is a division of my concurrent application Serial Number 84,598, filed January 29th, 1926 in which is shown a construction of binder employing similar methods but adapted to book or ledger form.

My invention has reference to binders employing leaves with undercut notches. Heretofore it has been a known practice to employ 20 therewith telescopic projecting posts carried by clamping plates of the binder, and means by which they can be manually projected into the notches. The disadvantage of the type of loose leaf binder referred to is that a material 25 addition to the space needed beyond the area of a single leaf has been necessary to accommodate the binding mechanism, and it has further been possible to leave the binding mechanism open when a person handling the 30 binder is careless so that the leaves may drop out of the binder and necessitate laborious re-assortment and loss of time. My present improvements obviate these disadvantages by providing that the mechanism for locking 35 the sheets is automatic in the locking direction when free, and is substantially contained within the superficial area of a leaf or mass of leaves when lying with their edges coincident. By this means the binder is never in 40 condition to allow leaves to come out, except when it is purposely operated by a bookkeeper or clerk, and considerable space is saved.

It should be noted that binders are known in which the leaves whereof have what may 45 be called notches of undercut form. There is, however, a material difference between such leaves and leaves according to my invention, in that the cut-out spaces of the latter are long recesses occupying generally at least 50 half of one end of a leaf or sheet, whereby the necessary space may be obtained within such recess for the manipulation of the lock-

ing means without any material excrescences beyond the area of a leaf or mass of the leaves when piled coincidently.

55

The method described in the present application provides for the manual operation of the securing mechanism, my concurrent application, Serial Number 84,599, showing a support device which may be adapted to operate mechanically the loose leaf securing mechanism or binder to release or to re-secure the leaves.

60

In the drawings annexed to this specification:

65

Fig. 1 is an outline of a leaf arranged with the central recess at one edge;

Fig. 2 is a view similar to Fig. 1 showing a leaf having a recessed edge formed by cutting away the corners of the leaf;

70

Fig. 3 is an end view looking from the anchoring end showing a bunch of leaves of the first kind and a filing structure according to my invention;

Fig. 4 is a sectional view on the line IV—IV of Fig. 3;

75

Fig. 5 is a plan view of a stiff sheet or cover board provided with rubber grips in the undercut ends terminating each recess; and

Fig. 6 is a section on the line VI—VI of Fig. 5.

80

Referring first more particularly to Figs. 1 and 2, 1 is a leaf or sheet formed in accordance with this invention with the recess 3 in one edge thereof, the terminations of the recess 3 being formed by the transverse undercut portions 4, 5 of the corner extensions 6 and 7 respectively.

85

In the leaf shown in Fig. 2, the recesses are formed by cutting away corner portions 12, 13, of the sheet, each recess being terminated at its innermost end by transverse undercuts 10 and 11 respectively and leaving a central portion 8 and 9 projecting from the edge of the sheet.

90

Preferably leaves as above will be formed with dimensions a , b , c , d , all equal, so that when cutting leaves from a long strip or a strip equal to a width of double the length of the leaf as illustrated in Fig. 1, leaves may 100 be cut therefrom without any waste by dividing the strip with transverse lines from either side of said strip. Alternatively, the said lines may finish in the middle of the recess

95

which will be formed in an opposite leaf; by thus cutting the strip, all the leaves will have the central recess as shown in Fig. 1. Should sheets as shown in Fig. 2 be desired, transverse cuts will be made starting from the opposite side of the sheet just mentioned, and finishing on the middle of the projections represented by *b*, *c*, of Fig. 2. In any event, if the sheets are to be cut without waste, the sum of the dimensions *a* and *d* must always equal the sum of the dimensions *b* and *c*.

If desired, a leaf 1 may have a corner 27 remote from the recessed edge cut away as shown in dotted lines in Figs. 1 and 2, in order to simplify reference to sheets in a pile.

Referring now to Figs. 3 and 4, a mass of leaves, such as 1 are here shown secured by anchoring bars 16, 17, occupying the undercut recesses 4, 5, in same. The said bars 16, 20 17, are attached by eyelet bushes 18, 19, provided at their lower extremity, to a spindle 20 secured by means of brackets 21, 22, to a base board 23, said brackets 21, 22, also functioning as abutments which limit the movement of the anchoring bars 16, 17, if and when the file be emptied.

The anchoring bars 16, 17, are normally retained in the undercut ends 4, 5, of the recesses 3 by a spring 26, which in the construction shown surrounds the spindle 20 and abuts against the eyelet bushes 18, 19, situated at its respective ends, and thus retains the latter in engagement with their respective terminations of the recess 3.

35 Finger plates or lugs 24, 25, may be provided extending laterally from the eyelet bushes 18, 19, wherewith to operate the anchoring bars. When it is desired to release a leaf or leaves from the mass, the anchoring bars 16, 17 are withdrawn into the recess against the resistance of the spring 26 by pressing the finger plates 24, 25, towards each other. One or all of the leaves may then be withdrawn or more leaves added, and on release of the finger plates 24, 25 the anchoring bars 16, 17, again take up their position in the undercut terminations 4, 5, of the mass of leaves, and thus firmly secure them.

A stiff sheet or cover board 28, is preferably provided to hold the leaves down so as to overcome any tendency for them to become displaced vertically.

At the upper ends of the anchoring bars 16, 17, are shown enlarged stud portions 14, 55 15, respectively which complement the effect of the cover board 28 when the file is overloaded.

Figs. 5 and 6 are more detail views of a retaining sheet or cover board 28 wherein, in order to enhance the frictional grip of said cover board with the anchoring bars 16, 17, the undercut terminations 4, 5, thereof are provided with linings 30, 31, of resilient adhesive or friction material, such as rubber.

65 In use, the file is simple and foolproof to

handle, any desired leaf being turned up immediately, owing to the fact that the whole mass of sheets may pivot on the spindle 20, and it is thus rendered possible to refer to the file without removing it from its cabinet, 70 supposing the anchoring end is outermost.

What I claim is:—

1. Apparatus for securing loose leaves of the kind having on one edge open recesses with undercut ends, having in combination 75 a pair of relatively movable anchoring bars and resilient pressure means associated with said bars adapted when tensioned to permit disposal of the bars within the area of the recess, and when released to automatically 80 lodge the bars within the undercut ends.

2. Apparatus for securing loose leaves of the kind having on one edge open recesses with undercut ends, having in combination anchoring members disposable within the 85 area of said recesses when a mass of leaves are coincidentally assembled and adapted to occupy the said undercut ends, resilient pressure means lodging said members in said undercut ends and permitting movement of 90 said members relative to the recess to effect release of the leaves.

3. Apparatus for securing loose leaves of the kind having on one edge open recesses with undercut ends, having in combination 95 anchoring bars disposable within the area of such recesses, a spindle on which one end of each of said bars is slidably mounted, and resilient means for normally maintaining the said bars in the undercut ends to secure the 100 leaves.

4. Apparatus for securing loose leaves of the kind having on one edge open recesses with undercut ends, having in combination 105 anchoring bars disposable within the area of such recesses, when a mass of leaves are coincidentally assembled, an eyelet bushing at one end of each bar, a spindle threaded through said bushings, a base member carrying said spindle, and a compression spring interposed 110 between said bushings adapted to maintain the bars within said undercut ends.

5. Apparatus for securing loose leaves of the kind having on one edge open recesses with undercut ends, having in combination 115 anchoring bars disposable within the area of such recesses when a mass of leaves are coincidentally assembled, an eyelet bushing at one end of each bar, a spindle threaded through said bushings, a base board, brackets secured to said base board, carrying said spindle, and a coil spring between said bushings and threaded on said spindle tending to maintain the bars in anchoring position, the said brackets being disposed to limit the outward 125 sliding movement of the said bars.

6. Apparatus for securing loose leaves of the kind having on one edge open recesses with undercut ends, having in combination anchoring bars disposable within the area of 130

such recesses, when a mass of leaves are coincidentally assembled, an eyelet bushing at one end of each bar, a spindle threaded through said bushings, a base member carrying said spindle, a compression spring interposed between said bushings adapted to maintain the bars within said undercut ends, and finger plates provided on said bushings.

7. Apparatus for securing loose leaves of the kind having on one edge open recesses with undercut ends, having in combination anchoring bars disposable within the area of such recesses when a mass of leaves are coincidentally assembled, an eyelet bushing at one end of each bar, a spindle threaded through said bushings, a base board, brackets secured to said base board, carrying said spindle, and a coil spring between said bushings and mounted on said spindle tending to maintain the bars in anchoring position, the said brackets being disposed to limit the outward sliding movement of the said bars, and finger plates provided on said bushings.

8. A cover for loose leaves, said cover having on one edge an open faced recess with undercut ends and reinforcements of frictional gripping material positioned in said undercut ends.

9. A cover for leaves, said cover having on one edge an open recess with undercut ends, a sheath bounding each of said undercut ends adapted to frictionally adhere to the anchoring bars of a securing mechanism for said leaves.

10. Apparatus for securing loose leaves of the kind having on one edge open recesses with undercut ends, having in combination anchoring bars disposable within the area of such recesses, when a mass of leaves are coincidentally assembled, an eyelet bushing at one end of each bar, a spindle mounted in said bushings, a base member carrying said spindle, a compression spring interposed between said bushings adapted to maintain the bars within said undercut ends, and a reinforced cover board, having a recess on one edge with undercut ends of each provided with a sheath of friction material to enhance the frictional grip on said bars.

11. Apparatus for securing loose leaves of the kind having on one edge open recesses with undercut ends, having in combination anchoring bars disposable within the area of such recesses when a mass of leaves are coin-

cidentally assembled, an eyelet bushing at one end of each bar, a spindle threaded through said bushings, a base board, brackets secured to said base board, carrying said spindle a coil spring between said bushings and mounted on said spindle tending to maintain the bars in anchoring position, the said brackets being disposed to limit the outward sliding movement of the said bars, and a reinforced cover board, having a recess on one edge with undercut ends each provided with a sheath of friction material to enhance the frictional grip on said bars.

12. Apparatus for securing loose leaves of the kind having on one edge open recesses with undercut ends consisting of anchoring bars disposed within the area of said recesses when a mass of leaves are coincidentally assembled, a spindle on which said bars are slidably and pivotally mounted, a base board, brackets secured to said base board carrying said spindle, and resilient means for normally retaining said bars in said undercut ends to secure the leaves, the mass of the leaves and said bars being adapted to pivot bodily about said spindle on the leaves being displaced for reference purposes.

13. Apparatus for securing loose leaves of the kind having on one edge open-faced recesses with undercut ends, comprising in combination a pair of anchoring members disposable within the area of said recesses when a mass of said leaves are piled coincidentally, means for guiding said anchoring members for lateral movement within the recesses to lock or release the leaves, and means for automatically and simultaneously returning said anchoring members into said undercut ends to lock the mass of said leaves.

14. In apparatus for securing loose leaves of the kind having one edge cut away to provide an open-faced recess with undercut ends, that part cut away being substantially equal in width transversely to the sum of the widths of the parts remaining, the combination with anchoring bars disposed in the area of the recess; of supporting means on which one end of each of said bars is movably mounted, and resilient means for normally maintaining said bars in the undercut ends to secure the leaves.

In testimony whereof I affix my signature.

RICHARD F. POWER.
